UNITED STATES PATENT OFFICE

GEORGE HEGEMAN HART, OF WEST HARTFORD, CONNECTICUT

ELECTRIC SWITCH

Application filed July 28, 1928. Serial No. 295,889.

My invention relates to electric switches, such, for example, of the type having one or more switch blades adapted to be snapped into and out of engagement with terminals or contacts positioned on a suitable base, and it has particular reference to contact posts.

The aim of the invention is to provide improved contact posts for electric switches having various features of novelty and advantage.

More particularly, the object of the invention is to provide an improved contact post which is extremely simple in construction, which can be very economically manufactured and assembled, which will permit of the wire being secured thereto with ease and facility, which will securely hold the wire, and which will not interfere with the cover of the switch irrespective of the size of the wire connected to the post.

Other objects will be in part obvious and in part pointed out more in detail hereinafter.

The invention accordingly consists in the features of construction, combination of elements and arrangement of parts which will be exemplified in the construction herein-after set forth and the scope of the application of which will be indicated in the appended claims.

In the accompanying drawing, wherein I have shown, for illustrative purposes, one embodiment which the present invention may take:

Figure 1 is a side elevational view of a switch equipped with contact posts constructed in accordance with the present invention, parts being in section;

Fig. 2 is a top plan view of a contact post partly in section;

Fig. 3 is an edge view of one of the posts;

Fig. 4 is a blank from which the body portion of the post shown in the preceding figures may be formed; and

Fig. 5 is a perspective view showing another embodiment of the invention.

In this drawing, I have shown, for purposes of exemplification only, my improved contact posts applied to a switch of a well-known construction, it having a base A

of insulating material, a handle B for turning the spindle (not shown); and a switch member or unit C having one or more blades.

Suitable devices (not shown) may be provided for throwing the switch member or members, when the spindle is rotated, with a sharp snap action into and out of engagement with the terminals. The switch has a cap or cover D.

In accordance with the present invention, each of the contact posts has a body portion preferably formed by stamping out from sheet metal a blank of the desired configuration. A blank from which a post may be formed is shown in Fig. 4. The body portion of the post is of generally angular shape and has a central or vertical web 10 and one or more horizontal webs. In the embodiments shown for illustrative purposes, each post has a pair of horizontal webs or arms 11 and 12. In the embodiment shown in Figs. 1 to 4 inclusive, one of the arms is provided with an integral contact 13. Obviously, each arm 11 and 12 may carry a contact, as shown in Fig. 5 wherein the arms 11 and 12 terminate in contacts 13 and 13' respectively. The contact 13 is offset slightly from the plane of the arm 12, but in certain instances, such an arrangement is not necessary. The side edges of the contacts are beveled, as at 14, so that they are more or less wedge shape in cross section. The bottom web 12 is adapted to seat on the base A and is provided with a suitable number of threaded openings 15. Screws 16 are adapted to project up through the base and to be screwed into these openings for the purpose for holding the post in place. The upper web 11 and lower web 12 are respectively provided with central openings 17 and 18 through which a wire 19 may be threaded, as shown most clearly in Fig. 1.

For the purpose of securing the wire in place, there is provided a clamping plate 20 adapted to be drawn towards the vertical web 10 by one or more screws 21, two such screws being shown in the present instance by way of illustration.

The clamping plate 20 may have, between its ends, an offset portion or corrugation

forming a vertical groove 22 which constitutes a seat for the wire 19. The screws 21 extend loosely through counterbored openings 25 in the vertical web and are 5 screwed into holes 26 in the clamping plate 20.

From the foregoing description, taken in connection with the accompanying drawing, it will be seen that my improved contact post, 10 while being simple in construction, is strong and effective. The post may be economically manufactured, it may be easily applied, and an electrical wire or conductor may be securely clamped thereby with facility. It 15 will be observed that the vertical web 10 is just inside of the cylindrical wall of the cover and is parallel thereto. The screws 21 extend freely through the vertical web, and the heads of these screws are adapted to 20 seat on the web. With this arrangement, the screws do not interfere with the positioning of the cover on the switch as would be the case if the screws had threaded relation with the vertical web and a thick wire was 25 to be clamped.

As many changes could be made in the above construction and many apparently widely different embodiments of this invention could be made without departing from 30 the scope thereof, it is intended that all matter contained in the above description or shown in the accompanying drawing shall be interpreted as illustrative and not in a limiting sense.

35 It is also to be understood that the language used in the following claims is intended to cover all of the generic and specific features of the invention herein described and all statements of the scope of the invention 40 which, as a matter of language, might be said to fall therebetween.

I claim as my invention:

1. A contact post for electrical switches having a web provided with an arm adapted 45 to be secured to a switch base, said arm having formed integrally therewith a contact, a clamping plate opposed to said web and having a pair of threaded openings, and a pair of screws extending through said web and 50 screwed into said openings.

2. A contact post for electrical switches comprising a member provided with a central web, a pair of arms, and a contact on at 55 least one of said arms; a clamping plate between said arms and opposed to said central web, said clamping plate having a threaded opening, and a screw extending through said web and screwed into said opening.

60 3. A contact post for electrical switches having a generally U-shaped member provided with a central web, a pair of arms, and a contact member extending from one of the arms; a clamping plate opposed to said web 65 and having a groove adapted to receive a

wire, said clamping plate having a pair of threaded openings, and screws extending through said web and screwed into said openings.
